UNITED STATES PATENT OFFICE

105,325

DESIGN FOR AN ESCUTCHEON PLATE

Achille G. Bureau, Forest Hills, N. Y., assignor to
Penn Hardware Company, Reading, Pa., a cor-
poration of Pennsylvania

Application December 9, 1936, Serial No. 66,404

Term of patent 7 years

To all whom it may concern:

Be it known that I, Achille G. Bureau, a citizen
of the United States, residing at Forest Hills, in
the county of Queens and State of New York,
have invented a new, original, and ornamental
Design for an Escutcheon Plate, of which the
following is a specification, reference being had
to the accompanying drawing, forming part
thereof.

Fig. 1 is a front elevation of an escutcheon
plate, showing my new design.

Fig. 2 is a longitudinal section of the same
taken on the line 2—2 of Fig. 1.

Fig. 3 is a cross-sectional view of the same
taken on the line 3—3 of Fig. 1.

I claim:—

The ornamental design for an escutcheon plate,
as shown.

ACHILLE G. BUREAU.
